UNITED STATES PATENT OFFICE

LELAND F. REESE, OF NEW YORK, N. Y.

REVERSIBLE REVOLVING DOOR, WEATHERSTRIP VERTICAL

Application filed November 29, 1930. Serial No. 499,070.

This invention relates to weatherstripping, and has for an object to provide a vertical weatherstrip particularly useful on a revolving door.

5 A further object of this invention is to provide a reversible vertical weatherstrip for a revolving door, so that it may be reversed and used over again when the first side is worn out, whereas the ordinary vertical weatherstrip on a revolving door would 10 have to be discarded.

Still another object of this invention is to provide a reversible vertical weatherstrip for a revolving door which will last twice 15 as long as the ordinary vertical weatherstrip, but will cost little, if any, more than the ordinary weatherstrip.

With the foregoing and other objects in view, as will hereinafter become apparent, 20 this invention comprises the constructions, combinations and arrangements of parts hereinafter set forth, described and claimed and disclosed on the accompanying drawings. In these drawings,

25 Figure 1 is a top plan broken view of a revolving door using this invention, and

Figure 2 is a perspective view of the weatherstrip as attached to the rubber base.

There is shown at 10 a revolving door, this 30 invention being shown as applied to one wing 11 thereof, the other wings being omitted to avoid duplication of disclosure. A quarter circle door jamb 12 is conventionally shown with a back support 13.

35 The vertical weatherstrip comprising this invention is shown at 14 in Figure 2, and is folded or looped about the opposite sides of its flexible base 15 to which it is secured by the lines of stitches 16. This flexible base

40 15 may be preferably of rubber having a reinforcing fabric 17 through the center thereof.

45 As shown, this base 15 is wedge shaped, and the short side of its wedge is slightly enlarged, as at 18 although one or both of

these enlargements or knobs may be omitted, if desired.

The base 15 is affixed to the door wing 11 by means of the strap 19 affixed thereto as by screws 20, the affixing means passing 50 through the base 15. If the knobs or enlargements 18 be present, the base and door may be shaped to fit, although of course in the absence of the door and strap being so shaped, these enlargements will be compressed as the strap is affixed due to their 55 flexibility. Due to the wedge shape of base 15, it will be securely held on the door wing 11 by the presence of the strap 19 as well as the screws 20.

In operation, the vertical weatherstrip 14 will slide along the jamb 12 until the loop 21 is almost or completely worn through in use. Then instead of discarding it and its base 15, or having a new strip sewed to the 60 base, the weatherstrip 14 and base 15 will be reversed by turning it upside down vertical, and thus a fresh and unworn surface to slide along the jamb 20, thus practically doubling 65 the life of the weatherstrip 14 at little if any 70 extra cost.

Having thus set forth and disclosed the nature of this invention, what is claimed is:

1. A reversible vertical weatherstrip for 75 revolving doors comprising a weatherstrip looped about and secured to opposite sides of the thin edge of a flat longitudinal resilient wedge shaped base.

2. A reversible vertical weatherstrip comprising a strip, a flat, longitudinal 80 wedge-shaped base, said strip being looped about opposite sides of the thin edge of said base, and common means for securing said strip to opposite sides of said base.

3. A reversible vertical weatherstrip comprising a strip, a flat, longitudinal, flexible base, said base being wedge shaped, and an enlargement on the short thick side of the wedge, said strip being looped about opposite sides of the thin edges of the wedge 85 90

forming said base, and common means for securing said strip to opposite sides of said base.

4. In a revolving door, a flat, longitudinal flexible base, a strap for detachably affixing said base to the door, said base being wedge shaped, a pair of knobs along the rear of said base, a weatherstrip looped about the free thin edge of said base and stitching 5 passing through the base to secure the weatherstrip thereto, whereby said weatherstrip with its base may be removed and reversed in position when worn on one side.

In testimony whereof I affix my signature.

15

LELAND F. REESE.
